UNITED STATES PATENT OFFICE.

IRVING H. SARE, OF SENTINEL, OKLAHOMA.

SPARK-PLUG.

1,150,392.

Specification of Letters Patent. Patented Aug. 17, 1915.

Application filed June 16, 1914. Serial No. 845,474.

To all whom it may concern:

Be it known that I, IRVING H. SARE, citizen of the United States, residing at Sentinel, in the county of Washita and State of Oklahoma, have invented certain new and useful improvements in Spark-Plugs, of which the following is a specification.

This invention relates to spark plugs and the primary object of the invention is to provide a plug of simple construction which may be readily applied to an engine and will be equipped with means whereby the spark will be spread and enlarged so as to produce a hot flame.

A further object of the invention is to provide a plug of simple construction which will permit the spark to be tested and adjusted at any time.

The stated objects and such other incidental objects as will appear as the description of the invention proceeds are attained in the use of such a device as is illustrated in the accompanying drawings, and the invention resides in certain novel features which will be particularly pointed out in the claims following the description.

In the annexed drawings, Figure 1 is a central longitudinal section of a spark plug embodying my present improvements; Fig. 2 is a horizontal section taken on the line 2-2 of Fig. 1.

In carrying out my invention I employ a base consisting of a sleeve 1 externally threaded, as shown at 2, whereby it may be easily secured in the wall of an engine cylinder and flared above the said threaded portion, as shown at 3, to provide a spark chamber. Above the flared portion 3 the base is provided with straight walls 4 and at the upper extremity of the said straight walls 4 is an externally threaded portion 5 to facilitate the attachment of a cap 6. The porcelain plug body 7 is provided with an annular rib 8, thereby presenting a lower shoulder 9 which is adapted to rest upon the upper end of the base, and an upper shoulder 10 against which the clamping action of the cap may be exerted. A spring gasket 11 is inserted between the top of the cap 6 and the shoulder 10 of the plug body 7 so as to effect a firm fastening between the cap and the base and at the same time accommodate any expansion which may take place in the plug body. Around the lower shoulder 9 of the porcelain body I secure a copper ferrule

or contact plate 12 which will be pressed into intimate engagement with the base and also with the cap 6, when arranged as shown in the present drawings, so that the terminal 13 which is embedded in the body 7 will have a direct grounded connection with the battery or the magneto. It will be noted that the terminal 13 extends through the body 7 and has its extremity projecting below the lower end thereof within the spark chamber, and this terminal, as well as the terminal 14, will be placed within the body when the same is manufactured. The extremities of the terminals 13 and 14 are spaced apart, as clearly shown in Fig. 1, and between the same I interpose a radiator or spreader 15 consisting of a ring or similar device having a shank or extension 16 which is embedded in the lower end of the porcelain body 7. This radiator or spreader will, of course, be insulated from and out of contact with both terminals.

The upper end of the terminal 14 projects slightly above the upper end of the porcelain body 7, as shown at 17, and around the upper end of the body 7 is fitted a metallic ring or annular wear-plate 18 which is externally threaded as shown, a sleeve 19 being threaded upon the said wear-plate. The upper end of the sleeve 19 is closed by a head 20 having a central threaded aperture in which is mounted a screw 21 having its lower end 22 normally arranged a short distance from but directly in axial alignment with the upper end 17 of the terminal 14. A transparent ring or sleeve 23 is fitted within the sleeve 19 and the said sleeve 19 is provided with openings 24 so that a spark passing between the end 22 of the screw 21 and the end 17 of the terminal 14 may be seen at all times. A lock nut 25 is mounted upon the screw 21 so that when the nut is turned home against the head 20 the screw will be locked in its adjusted position and a milled nut 26 is mounted upon the screw above the said lock nut so as to secure the end of a conducting wire firmly in place. If a conductor having a spring-socket terminal is employed, the said socket may be engaged over the spherical head 27 of the screw, and the said head is provided with a notch or slot 28 to permit the engagement of the screw by a screw-driver when adjusting the same.

It is thought the use and advantages of

my spark plug will be evident from the foregoing description taken in connection with the accompanying drawings.

The spark for supplying the charge in the engine is produced between the terminals 13 and 14 and, as it will impinge directly upon the spreader 15, it will be diverted laterally so that a large intense flame will be produced and the charge positively ignited. The condition of the battery or the magneto may be readily determined by viewing the upper spark gap through the openings 24, and the members 17 and 22 which produce the gap are all inclosed and protected against injury while at the same time they are always visible.

The device is exceedingly simple in the construction and arrangement of its parts and may be manufactured and applied to an engine at a very low cost.

Having thus described my invention, what I claim as new is:

1. A spark plug comprising a metallic base having a spark chamber in its upper portion, a body of insulation having an annular rib resting upon the upper end of said base and having its lower end disposed with-

in the spark chamber of the base, a contact plate on the underside of said rib bearing upon and forming an electrical connection with the base, a terminal leading from said contact plate through the body and projecting from the lower end of the same within the spark chamber, a second terminal extending through the body and projecting from the lower end thereof within the spark chamber and spaced from the first-mentioned terminal, and a cap fitting over said rib and engaging the base to clamp the rib thereto and secure the body thereon.

2. A spark plug comprising spaced terminals in axial alignment, and a spreader consisting of a ring interposed between and out of contact with the said terminals and disposed in a plane transverse to the axes of the terminals, the ring and the terminals being insulated each from the others.

In testimony whereof I affix my signature in presence of two witnesses.

IRAH. SARE.
